S. S. Thomas *ATTORNEY.*

Patented May 24, 1927.

UNITED STATES PATENT OFFICE.

JOHN HUGO SMITH, OF DETROIT, MICHIGAN, ASSIGNOR TO THE WESSON SALES COMPANY, OF DETROIT, MICHIGAN, A CORPORATION OF MICHIGAN.

TOOL HOLDER.

Application filed January 19, 1925. Serial No. 3,255.

My invention relates to a holder for counterboring or other tools, shown in the accompanying drawings and more particularly described in the following specification and claims.

One of the objects of this invention is to provide a tool holder comprising two separable co-operating elements adapted to be coupled together in driving relation—one of said elements being designed for connection with the spindle of a drill press or other machine, while the co-operating element is adapted to receive the shank of a boring or like tool; the construction being such that the first named element is adapted to adjust the element receiving the shank of the tool; whereby it may take up the wear of the latter.

A further object of the invention is to provide self-contained means for ejecting the tool from the socket of the holder when it is desired to remove or replace the same.

A further object of the invention is to provide means for securely locking the tool holder in the socket of its co-operating element secured to the spindle of the drill press and to insure a positive driving connection therewith.

With the foregoing and other objects in view which will appear as the description proceeds the invention further resides in the combination and arrangement of parts and in the details of construction hereinafter described and claimed it being understood that changes may be made in the precise embodiment of the invention herein disclosed without departing from the spirit of the same.

In the drawings accompanying this specification:

Figure 1 is a side elevation of the two co-operating elements comprising the holder in assembled relation, with a portion broken away to disclose the locking key in the upper socket of the holder extending into a longitudinal groove formed in the shank of the lower detachable element.

Figure 2 is a cross-sectional view taken on or about line 2—2 of Figure 1, through the upper and lower co-operating portions of the holder in assembled relation.

Figure 3 is a cross-sectional view taken on or about line 3—3 of Figure 5, through the lower portion of the holder.

Figure 4 is a cross-sectional view taken

on or about line 4—4 of Figure 6, through the upper portion of the holder.

Figure 5 is a vertical cross-sectional view through the lower detachable portion of the holder receiving the shank of the tool. 60

Figure 6 is a similar sectional view with parts in elevation of the upper portion of the holder supported in the spindle of a drill press.

Figure 7 is a cross-sectional view—taken on or about line 7—7 of Figure 5—through the planetary gearing housed within the lower portion of the holder. 65

Figure 8 is a fragmentary elevation of the lower detachable element of the holder—70 the annular gear-collar being removed to disclose one of the planetary gears, journaled in a peripheral groove in the holder.

Figure 9 is a cross-sectional view through the lock nut for retaining the annular gear collar in position—taken on or about line 9—9 of Figure 5. 75

Figure 10 is a cross-sectional view—taken on or about line 10—10 of Figure 6—through the retaining screws for supporting the adjustable screw shaft, journaled in the upper portion of the holder. 80

Figure 11 is a perspective view of a boring tool showing its diametrically disposed driving fins projecting from the tapering shank, adapted to enter corresponding recesses provided in the socket of the lower detachable portion of the holder. 85

Referring now to the letters of reference placed upon the drawings:— 90

A denotes the upper portion of a tool holder adapted for connection with the spindle of a drill press or other machine.

B designates its tapering shank extending from the socket portion C, in which is housed a screw shaft D journaled at d and d¹ in the walls connecting the socket portion with the tapering shank. D¹ indicates a projecting flange overlapping a shoulder d² formed in the wall of the socket. 95

E indicates a plurality of retaining screws supported in the wall of the socket portion and overlapping the flange D¹ of the screw threaded shaft. E¹ denotes a split ring encircling the retaining screws and lodged in a concave recess provided for its reception in the ends of the screws. 105

F designates a gear formed on the upper end of the screw shaft D in mesh with a plurality of planetary gears G. 110

H indicates a manually rotatable collar provided with an internal annular gear in mesh with the planetary gears G, journalled in peripheral recesses formed in the wall 5 of the shank.

I represents a retaining nut, tapped to receive the threaded end of the shank, to secure the collar H in position.

J denotes a driving key projecting from a 10 longitudinal groove j formed in the socket portion C and secured thereto by rivets or other engaging means.

K indicates a co-operating element adapted to receive the tapering shank L of a boring or other tool. The shank L is provided 15 with feathers L^1 having parallel outer faces adapted to enter corresponding recesses M^1 in the tapering socket M of the tool holder, thereby providing a driving connection between the same.

N designates a tubular shank provided with a longitudinal groove N^1 adapted to receive the driving key J of the co-operating portion of the holder A. The tubular 25 shank is also tapped at N^2 to receive the shaft D of the connecting element.

P denotes an adjustable shaft, screwed into the wall of the tubular shank, provided at its lower end with a relatively wide gear 30 P^1 in mesh with a plurality of planetary gears Q journalled in peripheral recesses formed in the wall of the tool holder. P^2 indicates an extension of the shaft P adapted to bear upon the end of the tool shank.

R indicates a manually rotatable collar formed with an internal annular gear R^1 in mesh with the planetary gears Q.

S denotes a nut screwed upon the shank of the holder adapted to retain the rotatable collar R in position.

T indicates a split ring encircling the nut having one end T^1 bent inwardly that it may enter a recess in the shank of the holder to secure the nut against accidental release.

Having now indicated the several parts by reference letters the construction and operation of my invention will be readily understood:

The upper portion A of the tool holder 50 is first engaged to the spindle of a drill press or like machine,—the lower co-operating portion of the holder is then fitted with a tool, as for example that indicated in Figure 11,—the projecting feathers L^1 of which enter the recesses M in the socket of the holder. The tubular shank N of the element K is then inserted in the socket C of the upper co-operating element,—the key J of the latter entering into the longitudinal 55 groove N^1 of the tubular socket. The shaft D is then screwed into engagement with the threaded end N^2 of the lower portion of the holder.

To take up any wear that may occur in 60 the tool the collar G is manually rotated,

thereby turning the shaft D through the co-operation of the planetary gears H,—the element K and the tool carried therein being thus raised or lowered and thereby adjusted relative to the upper supporting member and the work. 70

When it is desired to remove the tool from the socket of the lower member K the collar R is rotated—its annular internal gear rotating the planetary gears Q, thereby causing the shaft P to move downwardly between the planetary gears with which it remains in mesh—its end P^2 bearing against the end of the tool shank, forcing the latter outwardly and thus releasing the tool. 75

To detach the lower portion K from its co-operating supporting member A, the collar G is rotated so as to disengage the shaft D from the screw threaded end of the tubular shank N of the lower member, whereupon 85 the latter may be removed from the socket of its co-operating element.

Having thus described my invention what I claim is:

1. A tool holder of the character described, comprising two cooperating detachable interlocking members operating as a single unit, one of which has means adapted for driving connection with a power operated machine also means to receive and support the other member,—in turn adapted to support a cutting tool; means adapted for longitudinally adjusting said members while remaining in interlocking relation with each other and means carried by one of said members for forcing the tool carried thereby from its supporting socket each of said means including a screw and gearing for rotating the screw. 100

2. A tool holder comprising two cooperating detachable slidably interlocking members adapted to operate as a unit, one of said members having means adapted for driving connection with a power operated machine and also means to receive and support the other member,—in turn adapted to receive and support a cutting tool in driving relation therewith; a rotatable shaft carried by said first named member adapted to engage the second member; means for manually rotating said shaft, whereby the second member may be adjusted longitudinally in relation to the first member and means carried by the second member adapted to bear upon the end of the tool, whereby it 110 may be released from the socket of said member, said means including a screw and gearing for rotating the screw. 115

3. A tool holder comprising two cooperating members adapted to operate as a unit 125 and arranged in longitudinal alignment, one of the members forming an extension of the other member and having a shank fitting within and slidably interlocked with the same, one of said members having means 130

- adapted for driving connection with the spindle of a power driven machine and the other member being adapted to receive a cutting tool in driving relation thereto, 5 means adapted for longitudinally adjusting said members while remaining in interlocked relation with each other, said means including a screw and gearing for rotating the screw, a longitudinally movable shaft carried by the tool supporting member, and 10 manually operated means having a threaded shaft arranged to engage the end of the tool to release the latter from the member supporting it.
- 15 4. A device of the character described, comprising a member having a tapering socket and grooves to receive the tapering
- shank and fins of a cutting tool, said member having an interiorly threaded portion; a shaft provided at one end with a relatively wide gear and threaded at its opposite end to engage the interiorly threaded portion of said member; planetary gears journalled in peripheral recesses provided in said member in mesh with said gear; and a manually rotatable collar with an internal annular gear in mesh with said planetary gears, whereby upon rotating said collar the shaft may be longitudinally adjusted to bear upon the end of the tool shank to force the latter from the socket of said member. 20 25 30

In testimony whereof, I sign this specification.

JOHN HUGO SMITH.
